FREDERICK W. LINAKER AND THEODORE M. BRUBACK, OF DU BOIS, PENNSYLVANIA.

BOILER SOOT CLEANER.

Application filed September 25, 1923. Serial No. 684,688.

This invention relates to boiler soot cleaners of the type having a rotatable or oscillatable tube called the "cleaner element" for conveying steam or other cleaning fluid, such tube commonly being provided with jet nozzles for directing jets of such fluid against or among the boiler tubes. Such rotative elements, when located low enough to be within reach, are commonly turned by a hand wheel or handle on the end outside the boiler setting; or when located so high as to be out of reach, they usually carry a sheave wheel over which passes a chain extending down to where it may be grasped by the attendant; or in other cases a ratchet wheel is provided, which is turned by a pawl on a lever which is rocked by means of a chain or other connection extending down within reach of the operator. The best results are secured by an intermittent rotation of the element by mechanism of the ratchet type, whereby between the advancing impulses the jets remain stationary for a short time so as to enable them to do their cleaning work more thoroughly than when merely swung through a given arc.

The present invention provides an improved mechanism whereby the cleaner element may be rotated intermittently. In its preferred embodiment it is adapted to turn the element in either direction, so that the jets may be swung through an arc from a given starting point to a given stopping point and back again, so as to confine their operation to that sweep which alone is effective for cleaning the boiler tubes.

An embodiment of the invention is illustrated in the accompanying drawings, of which:—

40 Figure 1 is a longitudinal vertical sectional view;

Fig. 2 is an end view, with the cover plate of the valve casing removed, as seen from the line II—II Fig. 1.

45 Fig. 3 is a sectional view on the line III—III Fig. 1.

Fig. 4 is a horizontal sectional view through the lower part of the construction shown in Fig. 1.

50 Fig. 5 is a vertical sectional view on the line V—V Fig. 1.

Fig. 5^a is an enlarged view showing ratchet bar, stop means.

55 Fig. 6 is a sectional view on the line VI—VI Fig. 1, and

Fig. 7 is a vertical sectional view on line VII—VII Fig. 4.

Referring to the drawings, A, Fig. 1 is a portion of the boiler setting, B is the usual sleeve set therein, and B' is a cap thereon. 60 Within the sleeve and cap the cleaner element C is mounted, so as to be able to rotate in the manner well understood. This element commonly projects into the boiler and among the boiler tubes, and is provided with 65 nozzles at intervals from which jets of steam may be directed against or among the boiler tubes. The front or outer end of the element C projects through a stuffing box D into a casing or head E to which steam is admitted through a supply pipe F. The valve for controlling the admission of steam into the element may conveniently be located within the head E, or may be elsewhere applied, as may be desired in any individual 70 case.

A supporting frame G is fastened to any suitable stationary part. This frame G is conveniently made of plates g and g', connected by arms g², the plate g having an 80 annular portion engaging the head E, as by embracing a boss on the latter, and being fastened by tap screws, while the plate g' supports the element C through an anti-friction bearing g³. The frame G provides 85 the bearing for a rotary shaft L on which is fixed a pinion M which meshes with a gear N fixed on the tubular element C. A set-screw n serves for fastening the gear N to the element. 90

The shaft L has fixed thereon a ratchet wheel O, and on each side thereof, on the shaft L, are the hubs p and q of two oppositely arranged ratchet levers P and Q, having the spring-pressed pawls p', q' thereon 95 adapted to engage the teeth of the ratchet wheel O in opposite directions.

Between the levers P and Q there is arranged a projection or block R on the supporting frame G and having stops r¹, r² 100 thereon coacting with stops r⁴, r⁵ on the lever P, and stops r⁶, r⁷ on the lever Q for limiting the throw or movement of these levers.

The levers P and Q are normally pressed to an initial position (see Fig. 2), and for 105 this purpose a spring S is provided wound around the shaft L and has its two ends s¹, s² connected to the levers P and Q as indicated at s⁴, s⁵, the reaction of the spring being to draw the two levers together with 110

the stops p^4, r^7 thereon against the shoulders r^1, r^2 of the block R.

Projecting from the block R in the path of the pawls p, q , are two cam-projections or horns r^{10}, r^{11} , which when the levers P and Q are in initial position (Fig. 2) hold the pawls p, q thereon out of engagement with the teeth of the ratchet O, allowing these pawls to engage said teeth, however, when one or other of said levers is moved away from its initial position, as shown in Fig. 5.

It is generally desirable to provide for stopping the rotation of the element after it has turned through a given arc, in order that the operator may then be compelled to reverse its direction and cause its jets to swing backwardly through the same arc. This is because in most installations the jets are effective during only a limited part of an entire revolution, so that to perform the remainder of the revolution would be a waste of time and steam. In such cases it is desirable to provide adjustable means for limiting the rotative movement of the element. Such means are shown in Figs. 1 and 6, where Y is an adjustable stop piece fastened to the gear wheel N by means of a bolt or screw y . The stop piece Y has pins y^1, y^1 projecting from it, which enter holes y^2 formed in the wheel N, the bolt y going through an intermediate hole. The holes y^2 and the spacing of the pins y^1, y^1 have such angular relation as to enable the stop piece Y to be set around step by step in any suitable succession of angular positions to which it may be set in the original installation and adjustment of the apparatus. The stop piece Y strikes a part of the shaft L, but it may strike any other suitable part for performing its stopping function. As shown in Fig. 6, it will permit nearly an entire revolution of the element; to confine the element to some lesser arc, two stop pieces Y may be employed, a second one being indicated in dotted lines at Y' .

Operation: The initial position of the parts, with the valve E controlling the admission of cleaning fluid to the element C closed, is illustrated in Fig. 2. To operate the mechanism to clean the boiler tubes, the workman pulls on one or the other of the chains attached to the ratchet levers, P or Q (which ever may be necessary to turn the parts in the proper direction). In this case, the lever Q would be first pulled. This would cause the spring pressed pawl q^1 thereon to slide off of the cam-projection r^{11} , and to engage one of the teeth on the ratchet wheel O. Movement of the lever Q would turn the ratchet wheel O to the extent permitted by the stops r^8, r^7 thereon in relation to the shoulders r^1, r^2 on the block R. As here shown a single pull on one of the ratchet levers P or Q effects a rotation of

about 45° of the ratchet wheel O. The ratchet wheel O being fast on the shaft L, turns the latter, and this in turn rotates the pinion M in mesh with the gear N fixed to the element C. As the gear N is of considerably greater diameter than that of the pinion M, a rotation of 45° of the pinion M would effect a considerably less degree of rotation of the gear N and the element C turned thereby. For example, each pull of a ratchet lever might be designed to effect a rotation of about 5° of the gear N and element C, so that to turn the element C through an arc of 135° would require 27 pulls or operations of one of the ratchet levers. The operation of the ratchet levers through the gears M and N therefore effects a comparatively slow and relatively steady or uniform rotation of the element. The mechanism thereby compels or imposes upon the workman a mode of operating the cleaner element which is independent of his skill or instructions for operating the cleaning mechanism, and insures the thorough and effective cleaning of the tube system in the zone cared for by the element operated, and by choosing a proper ratio between the pinion on the ratchet wheel shaft and the gear on the element, a rate of turning of the element best suited in general practice for the cleaning of the tube system and an economical use of steam, may be closely approximated.

After each pull of a ratchet lever, upon releasing the chain, it is restored to initial position by the spring S.

The degree of rotation of the element C may be controlled by the stop or stops Y, Y^1 .

The construction is preferably arranged for reverse operation. When so arranged, when the workman finds that the mechanism is stopped when he continues the intermittent pulling on one lever, he then grasps the chain attached to the opposite ratchet lever (the ratchet lever P in the sequence pertaining to the structure illustrated) and begins repeatedly pulling upon said opposite ratchet lever. This operates in the same manner as the other ratchet lever, but in an opposite direction, to turn the ratchet wheel O, and this through the shaft L, pinion M and gear N pulls the element C intermittently in the reverse direction.

The movement of the element C in the opposite direction may be controlled by the stops Y, Y^1 , on the gear N, or, as here shown, the construction of the valve in the casing E may be such as to limit the reverse movement of the element, and when the element reaches the limit of its reverse movement, admission of cleaning fluid to the element is cut off, and the cleaning completed.

The present invention provides a very simple and inexpensive construction for imparting the desired intermittent rotation to

the cleaner element. The device is applicable for use at any elevation, and may be very conveniently operated, its use requiring no special skill. The operator has only to repeatedly pull and release one chain until further turning is stopped, and then change to the other chain for intermittently rotating the element back to its starting point; this operation may be repeated if found necessary for effective cleaning.

The valve in the casing E illustrated herein, and the combination of such valve broadly with means for automatically opening and closing it by the same means which are used for turning the element, is not claimed herein, but is claimed in another of our applications, to wit:—our application Serial No. 641,149, filed May 24, 1923.

The combination of a step by step mechanism for turning the cleaner element with means for automatically opening and closing the valve is described and claimed in our application No. 634,524, filed April 25, 1923.

The invention may receive other embodiments than that herein specifically illustrated and described, within the scope of the appended claims.

What is claimed is:—

1. A soot cleaner comprising an element adapted to project jets of cleaning fluid into a bank of tubes, means for intermittently turning said element in either direction, said means comprising ratchet levers co-axially pivoted carrying pawls, a ratchet wheel operatively connected to said element and adapted to be engaged by either pawl when its lever is actuated, and a frame supporting said ratchet levers and wheel, and carrying a stop, each of said levers being provided at its hub portion with two shoulders integrally formed therewith and adapted to engage said stop whereby their motion in either direction is limited to a definite arc.
2. A soot cleaner comprising an element adapted to project jets of cleaning fluid into a bank of tubes, means for intermittently

turning said element, and a reduction gearing between said turning means and said element adapted to impose on said turning means a relatively slow intermittent turning of said element, said means comprising ratchet levers, adapted to operate in opposite directions, a pawl on each lever, a ratchet wheel adapted to be engaged by said pawls, and a cam for lifting each pawl out of engagement with said ratchet wheel on its return movement.

3. A soot cleaner comprising an element adapted to project jets of cleaning fluid into a bank of tubes, means for intermittently turning said element, and a reduction gearing between said turning means and said element adapted to impose on said turning means a relatively slow intermittent turning of said element, said means comprising ratchet levers, adapted to operate in opposite directions, a pawl on each lever, a ratchet wheel adapted to be engaged by said pawls, a cam for lifting each pawl out of engagement with said ratchet wheel on its return movement, and spring means for returning said levers after each operation.

4. A soot cleaner comprising an element adapted to project jets of cleaning fluid into a bank of tubes, means for intermittently turning said element, and a reduction gearing between said turning means and said element adapted to impose on said turning means a relatively slow intermittent turning of said element, said means comprising ratchet levers, adapted to operate in opposite directions, a pawl on each lever, a ratchet wheel adapted to be engaged by said pawls, a cam for lifting each pawl out of engagement with said ratchet wheel on its return movement, and spring means for returning said levers after each operation, said means being a single coil spring attached at its ends to said levers.

In witness whereof, we have hereunto signed our names.

FREDERICK W. LINAKER.
THEODORE M. BRUBACK.
